UNITED STATES PATENT OFFICE.

KONRAD OLSEN, OF TACOMA, WASHINGTON.

ELECTRIC HAMMER.

Application filed August 16, 1926. Serial No. 129,545.

This invention relates to electrically driven percussion tools, such as hammers and chisels, and has for its objects to improve the construction of such a tool whereby, first, the 5 spring delivering the blow will be of considerable length and may therefore be comparatively heavy, thereby delivering a strong blow without overstrain; second, the electric motor may run at a very high speed, and 10 therefore may be of comparatively small dimensions and weight; third, the gears interposed between the motor and the actuating cam are of the spur gear type and are mounted within an oil bath and therefore are extremely rugged in construction and of long 15 life; fourth, the hammer portion of the tool may be removed from the motor portion thereof and, since the drive shaft is of comparatively slow speed, a drilling tool may be 20 mounted thereon, thereby permitting the same electric equipment to be applied to a plurality of types of tools; and fifth, the speed of the blows is high in spite of the low speed of said drive shaft. A further object 25 is to provide such an electrically driven tool which will be of low cost to manufacture and to operate and which will be highly efficient in use.

I attain these and other objects by the 30 mechanisms, devices and arrangements illustrated in the accompanying drawings, in which:—

Fig. 1 is a side elevation, partly in section, to reveal the interior of the gear box, of the 35 electric motor portion of my improved tool, the hammer portion thereof having been removed; Fig. 2 is a horizontal section of my improved hammer, showing the electric motor portion therein in plan; Fig. 3 is a side 40 view of the complete tool, showing the hammer portion and a portion of the gear box in section; Fig. 4 is an end elevation of the motor portion after the hammer portion of the tool has been removed and showing the operating cam; and Fig. 5 is a section of the frame 45 of the hammer portion, taken at the level of the line marked "A" in Fig. 3, with the plunger removed and showing the bushing therein.

50 Similar numerals of reference refer to similar parts throughout the several views.

Referring to the drawings, the electric motor 1 is preferably of the cylindrical type and is provided with a rapidly rotating armature shaft 2, projecting axially therefrom. The frame of the motor is provided with suit-

able securing flanges 3. The other details of the electric motor are not illustrated herein as they form no part of my invention.

A gear box 4, preferably of about the same 60 diameter as the electric motor 1, is provided with securing flanges 5, complementary to the flanges 3 on the motor, and the two parts are secured together by bolts 6, or otherwise. The gear box 4 comprises a hollow casting 65 forming a space 7 within which the gears are mounted and forming an oil compartment adapted to be filled with oil or grease. A wall 8 is secured within the box 4 to form a closure for the said oil compartment 7. A 70 drive shaft 9 is mounted in a broad bearing formed in the wall 8, coaxial with the armature shaft 2 of the motor. A counter shaft 10 is mounted parallel with the shafts 2 and 9. A pinion 11 is mounted on the armature shaft 75 2 and meshes with a larger gear 12 on the counter shaft 10, and this shaft also carries a pinion 13, which meshes with the larger gear 14 mounted on the drive shaft 9. Thus the drive shaft 9 turns in the same direction 80 as the armature shaft 2 but at a much lower speed.

The cylindrical walls of the gear box 4 extend out beyond the above mentioned closure wall 8 and thus form a cam chamber 15 85 in the end of the gear box. The said drive shaft 9 projects into the said cam chamber 15 and may be screw-threaded at its end, or provided with other securing means if desired. The box 4 is also provided with securing flanges 16 at the cam chamber end thereof. As shown in Fig. 1, when the hammer portion of the tool is removed, the cam chamber 15 is open and the end of the drive shaft 9 is exposed and is adapted to receive a drill 90 chuck, or other tool-securing means.

A cam disk 17 is mounted in the chamber 15 and is provided with a central boss 18 adapted to screw on the end of the drive shaft 9. The disk 17 is cut away on its outer face, as shown in Figs. 3 and 4, to form three or more curved eccentric cam surfaces 19, each leading inward from an outer concentric circular arc 20 and terminating in a radial surface 21 leading outward from the inner end 95 of the eccentric surface 19 to the arc 20.

The hammer part of the tool comprises a frame having a circular disk or plate 22 with flanges 23, complementary to the flanges 16 of the gear box 4, said plate being adapted to close the cam chamber 15 when secured thereon by bolts 24, passing through the said 100 105 110

flanges 16 and 23. The plate 22 is preferably formed integral with the tubular hammer casing 25 which extends with its axis at right-angles to the axis of the motor 1 and gear box 5. The casing 25 is provided with a removable handle 26, of conventional form, and containing an electric switch operated by the lever 27, in the usual way. The power wires lead to the handle 26 through a push plug 28, 10 as usual, and the wires leading from the handle 26 to the motor 1 may also be connected to the handle 26 by a suitable push plug 29, if desired, whereby, when the motor 1 is used independent of the hammer, it may 15 be quickly disengaged from the handle 26. A slot 30 is formed through the side wall of the casing 25 and the plate 22, connecting the lower part of the cam chamber 15 with the inside of the said tubular casing 25 and 20 adapted to permit the operating pin to freely reciprocate therein. A bushing is mounted in the lower end of the tubular casing 25, the upper end 31 of which is provided with a square axial hole and the lower end 32 with 25 a circular axial hole, the diameter of the latter being equal to the diagonal of the former (Fig. 5). A hammer plunger is mounted in the tubular casing, said plunger comprising a square sectioned striking head 33, mounted 30 in the square hole in the bushing and projecting down therefrom into the round hole therein, and adapted to forcefully strike whatever tool end may be mounted in the said round portion of the bushing; a cylindrical operating head 34, above the striking head 33 and above the bushing 31; and a long 35 upper shank 35, extending through a screw plug 36 in the upper end of the tubular casing 25. A strong helical spring 37 is mounted 40 within the casing 25, surrounding the shank 35, and is compressed between the plug 36 and the upper surface of the operating head 34, and is adapted to strongly drive the operating head 34 and striking head 33 when 45 the head 34 is released. An operating pin 38 passes horizontally through the operating head 34 and projects through the slot 30 and into the cam chamber 15, and is provided with a roller 39 at its end, adapted to engage 50 the eccentric cam surface 19 and to be raised thereby to compress the spring 37, as the cam rotates, and to be released when the radial surface 21 is reached, whereby the hammer plunger is released. The length of the slot 55 30 is such that when the plunger is at either end of its stroke the pin 38 is free from engagement from the end of the slot, and the position of the bushing 31 is such that the operating head 34 will be in engagement 60 therewith before the roller 39 comes in contact with the circular arc 20 of the cam, thus

the pin and the cam disk are both relieved of all the shock of the hammer blows, and the full force thereof is received by the tool in the bushing 32. Also the square bushing 65 31 carries all the torque due to the action of the cam 19 on the pin 38 and therefore there is no wear of the said pin on the sides of the slot 30. It will also be observed that the shank 35 is mounted between bearings in the parts 31 and 36 and that the operating force is applied thereto between the said bearings, and that therefore the operating force may be applied thereto in a line outside of the axis of the hammer without having to make 70 the said parts heavy to overcome the bending moment applied thereto. It will also be observed that with this arrangement of parts it is possible to use a much longer spring 75 without lengthening the whole tool than would be possible with the motor coaxial with the hammer. Also that though the motor is of high speed, the drive shaft is of low speed and is therefore adapted for other uses than with this particular hammer, and that though the drive shaft is of low speed 80 the reciprocations of the hammer are of high speed. Also that the circular arc of the cam between each radial part and the adjacent cam part gives a moment of contact of the hammer striking head with the tool being engaged and this kind of a blow is much more effective than if the cam surface engaged the operating pin as soon as the blow had been struck. 85

Having therefore described my invention, what I claim is:—

In an electric hammer, the combination of a main tube, having a handle attached to one end; a bushing in the other end of the tube and adapted to receive the tool; a bearing bushing adjacent said tool bushing; a second bearing bushing at the handle end of the tube; a hammer rod extending within said tube through both said bearing bushings, and 100 adapted to reciprocate therein; a weight secured to said rod, between the bearing bushings and near the lower end thereof; a long helical spring mounted within said tube and surrounding said hammer rod and compressed between said upper bearing bushing and said weight, whereby said rod, with the weight, is actuated downward to engage the tool; a cam arranged adjacent said weight 105 and rotating on an axis at right angles to the axis of said rod; and a pin secured to said weight and engaging said cam, whereby the weight is raised against the action of said spring and is released to be driven by said spring against said tool. 110 115

KONRAD OLSEN.
